UNITED STATES PATENT OFFICE.

CARL EGGART, OF ARBON, SWITZERLAND, ASSIGNOR TO SOCIETE ANONYME ADOLPHE SAURER, OF ARBON, SWITZERLAND, A CORPORATION OF SWITZERLAND.

LOOM.

Application filed September 19, 1925, Serial No. 57,285, and in Germany December 17, 1924.

Warp beams for looms are commonly provided in the peripheral surface with a longitudinal groove or depression to receive the knotted ends of the warp so that such knotted ends shall not protrude beyond the peripheral surface of the beam and destroy the true cylindricity of the mass of warp when wound on the beam. For the same general purpose it is desirable to provide a covering plate, curved upon the radius of the beam, to cover the groove or depression referred to and so preserve the cylindricity of the mass of warp. The present invention has for its object to provide improved means for the placing of such covering member, so that in beginning the winding of the warp upon the beam the covering member shall place itself in position over the groove and over the knotted ends of the warp in the groove, thus restoring the true cylindricity of the beam as a support for the warps. In accordance with the invention the curved covering plate is secured to the cloth which is itself secured to the warp beam and at its other edge has the knotted ends of the warps secured to it, so that in the beginning of the winding operation, as the attaching cloth is wound on the beam, the curved covering plate carried by it is placed over the groove in the beam, thereby preserving the true cylindricity of the support on which the warps are wound. The invention will be more fully described hereinafter with reference to the accompanying drawing in which it is illustrated and in which:

Figure 1 is a top view showing a warp beam, the attaching cloth and the warp ends.

Figure 2 is a view in section of the same on a plane at right angles to the axis of the beam.

Figure 3 is a view similar to Figure 2 but

showing the attaching cloth and warps wound on the beam.

The warp beam *a* is flattened and grooved longitudinally as indicated at *b*, and has secured to itself one end or edge of the usual attaching cloth *f*, to the other end or edge of which, as indicated at *c*, the knotted ends of the warp threads *d* are secured as usual. Secured to the attaching cloth *f* is a covering member *e*, preferably a metal plate, curved upon the same radius as that of the warp beam and properly positioned so that, when the attaching cloth is wound upon the beam, as indicated in Figure 3, the covering member will be placed with its edges resting against the marginal portions of the flattened face of the warp beam and thereby cover the groove *b*, and the knotted ends of the warp threads and complete the curved peripheral surface upon the same radius as that of the beam, preserving the truly cylindrical form of the support for the warp threads which are wound on the beam over the attaching cloth and the covering member.

I claim as my invention:

The combination with a warp beam having in its peripheral surface a longitudinal groove for the reception of the knotted ends of the warp threads, of an attaching cloth secured to the warp beam and having the ends of the warp threads secured to it, and an independent covering member curved upon the same radius as that of the warp beam and secured to the attaching cloth in position to cover the groove in the beam as the cloth is wound thereon, together with the knotted ends of the warp threads, and thereby preserve the true cylindricity of the support for the warp threads.

This specification signed this 4th day of September A. D. 1925.

CARL EGGART,
